SAFETY DEVICE FOR CAN SEAMERS

John G. Harris, Enid, Okla., assignor to Swift & Company, Chicago, Ill., a corporation of Illinois

Application July 23, 1949, Serial No. 106,459

8 Claims. (Cl. 113—7)

1

The present invention relates to a safety guard for semi-automatic machines of a type exemplified by a can closing machine.

In a number of machines common in industry today the object upon which work is to be performed by the machine is clamped therein by being inserted into proper position by a manual operation, and two portions of the machine are brought together with sufficient force to hold the object in place. The clamping force may be manually applied or it may be a mechanical force, as from an electric or fluid motor, initiated by the actions of the operator. With these machines the operator must be constantly alert so as not to catch his hand or fingers within the machine when the clamping force is applied.

Typical of some of the machines in which this problem arises is a can closing machine in which a table is mechanically raised to bring the unsealed can into position against the machine head where the closing operation is performed. The cans are placed on and removed from the tables by the manual manipulations of an operator. Despite constant safety education and warnings the operators of such machines will "forget" and have a finger above or below the can when the table is raised. The result is a painful and often serious injury.

The present invention has for its principal object the providing of a safeguard for such machine which will prevent the operator from getting his hand caught in the machine solely as a result of "forgetfulness." At the same time the speed and efficiency of the machine and the operator is not impaired in the slightest degree.

The safety device is of a type that, should the operator attempt to insert the can or other object into the machine with the fingers being positioned other than at the sides of the can, such movement will be prevented until the operator moves his fingers to the proper position where they will not be caught.

Additional objects and advantages will become apparent from the following description taken in conjunction with the drawings, in which:

Fig. 1 is a front elevation of a can closing machine with the present invention positioned thereon.

Fig. 2 is a plan view of the safety device used with the machine of Fig. 1.

Fig. 3 is a section taken at line 3—3 of Fig. 2, and

Fig. 4 is a diagrammatic illustration of the relationships between the table, can-closing chuck, guard member, and can in the present invention.

2

The can closing machine illustrated in Fig. 1 includes a frame 13 carrying a loading table 14 and a machine head 15. The can closing machinery, the particular details of which form no part of the present invention, located in head 15 is operated by motor 16. The machine is adapted to secure a cover on the upper end of unclosed cans 17 which are manually transported across loading table 14 to a vertically movable inset 18 therein. The inset 18, or moving table, is moved up and down by suitable power means actuating vertically movable rod 19 connected to table 18.

After the can 17 on table 18 is brought into proper position to be raised into machine head 15, the operator depresses pedal 22 with his foot thereby initiating the vertical movement of rod 19 to raise the table. As the can 17 is raised by means of table 18 it passes into an aperture in the lower portion of head 15. Meanwhile, from a stack 21 of can covers, a feeding mechanism 20 has positioned a single can cover over the aperture into which the can is raised so that as the can is brought into position in the machine head 15 in contact with a conventional chuck (not shown), the position of the bottom of which is indicated, however, at 31 in Fig. 1, the cover and the can may be suitably folded and spun to close the can.

While the operators constantly are cautioned to keep their hands about the sides of can 17, ever so often one will forget and have a finger hooked over the top or bottom of the can at the time pedal 22 is depressed to initiate the machine action. Under such circumstances the operator's finger is caught either between the can and the table or between the can and the machine head with a resulting injury to the operator.

To prevent such accidents from occurring I have devised a safety device 24 which may be applied to a machine of this type and which is readily adaptable to other machines having a similar operating problem but being of somewhat different specific design. In the present instance the safety device 24 preferably includes a disc 25 to which is secured an angle 26 to act as a mounting bracket. The bracket is secured to frame 13 by suitable means such as stud bolts 27. The disc 25, substantially circular, has an opening 29 in an intermediate portion thereof. The opening 29 is of sufficient size, and properly positioned, to allow the can 17 to move therethrough as the can is brought to machine head 15 by the raising of table 18. In the illustrated embodiment a cut-out 30 is made in the disc 25 to allow for the movement of the feeding mechanism 20

in positioning a cover. With other machines not having the problem of such a feeding mechanism, the disc 25 is preferably a full circle.

The position of the bottom of the disc 25 with respect to the top of the can 17 as it rests on table 14 is particularly critical. That distance as represented by dimension *a* must be sufficient to allow the can to be easily moved across the table 14 and into proper position upon table 18. However, the distance must be sufficiently small so that the operator's fingers will not fit between the top of the can 17 and the bottom of disc 25, preferably the dimension *a* is not substantially greater than one-fourth of an inch. In other words, the throw or vertical rise of table 18, actuated by the vertical movement of rod 19, must be such as to bring the top of the can into engagement with the can-closing machinery in head 15, as is conventional in can-closing machines of this type.

It is also highly desirable that the safety device 24 be in the form of a disc rather than merely a ring "tell-tale." Through the use of a disc having an aperture 29 just sufficiently large to accommodate can 17, the operator is forced to remove his fingers from the ends of the can before the can will fit under the disc and normally is prevented from slipping a finger over the end of the can until it is again removed from the machine. While it is possible that an operator may intentionally get a finger above the can after it has been centered under aperture 29, it is extremely unlikely that this could be done as an unconscious movement. If the safety device consisted of only a ring having only a nominal width as measured parallel to the table 14, the operator might easily get into the habit of having a finger over the top of the can and by tilting the can in at an angle being able to pass the guard without removing the finger from the top of the can. The width of disc 25 between the periphery thereof and aperture 29 prevents any such procedure from occurring with my invention.

Referring to Fig. 4 of the drawings, a schematic illustration of the relative positions of the various elements is shown. The chuck or other conventional can-closing equipment is indicated at 31. As in the usual case, the table 18 moved by rod 19 raises the can to a closing position within chuck 31, at which position the attaching of the lid to the can takes place. When the can is at this closing position, the top of the can is at a given line 32 within chuck 31. Thus the amount that table 18 raises can 17 is indicated by dimension *b*. Guard 24 is positioned between the table 18 and the chuck 31 so that the spacing *c* between said line 32 in the chuck and the bottom of the guard 24 is equal to the distance of the table movement *b*, less a distance smaller than the thickness of a finger *a*.

The holes in bracket 26 for receiving bolts 27 are preferably elongated to facilitate adjustment of the distance between the disc 25 and the table 14 so as to accommodate different sizes of cans. Other means may be used to accomplish a similar purpose, such as a plurality of holes in bracket 26, or a plurality of tapped holes in frame 13 to receive stud bolts 27.

Thus, the guard may be readily added to existing machines and with a simple adjustment a machine may be set for the closing of one type of cans one day and another type of cans the next day. Despite the simplicity of installation and adjustment, the guard will assure that the necessary safety precautions are taken.

The foregoing description is for the purpose of

complying with Section 4888 of the Revised Statutes and should not be construed as including any unnecessary limitations upon the appended claims inasmuch as from the foregoing description, certain modifications will be apparent. For example, if the machine should be of a type in which the machine head 15 is movable in a vertical direction rather than table 18 being movable, the guard 24 should be at a fixed distance with respect to the head 15 and should move therewith.

I claim:

1. In a manually loaded can-closing machine the combination of a can-closing chuck member, 15 a table member adapted to support the can to be closed, one of said members being mounted for movement from a first position toward the other of the members a given distance to bring a can placed on said table member into sealing position 20 in said chuck member with the top of the can at a given line in said chuck member, and a guard disc positioned between said members and above said can, the spacing of the bottom of the guard disc from said line in said chuck member 25 being equal to said given distance less a distance smaller than the thickness of a finger.

2. In a manually loaded can-closing machine the combination of a can-closing chuck member, 30 a table member adapted to support the can to be closed, one of said members being mounted for movement from a first position toward the other of the members a given distance to bring a can placed on said table member into sealing position 35 in said chuck member with the top of the can at a given line in said chuck member, and a guard disc positioned between said members and above said can, said guard disc having a portion thereof cut away to allow the can to project therethrough as said movable member travels from 40 said first position toward the other of the members, the spacing of the bottom of the guard disc from said line in said chuck member being equal to said given distance less a distance smaller than the thickness of a finger.

45. 3. In a manually loaded can-closing machine the combination of a can-closing chuck member, a table member adapted to support the can to be closed, one of said members being mounted for movement from a first position toward the other 50 of the members a given distance to bring a can placed on said table member into sealing position in said chuck member with the top of the can at a given line in said chuck member, and a guard disc positioned between said members and above said can, said guard disc forming an aperture in a substantially central portion thereof to permit the can to be raised therethrough by the motion of said movable member, the spacing of the bottom of the guard disc from said line in 55 said chuck member being equal to said given distance less a distance smaller than the thickness of a finger.

60. 4. In a manually loaded can-closing machine the combination of a can-closing chuck member, 65 a table member adapted to support the can to be closed, one of said members being mounted for movement from a first position toward the other of the members a given distance to bring a can placed on said table member into sealing position 70 in said chuck member with the top of the can at a given line in said chuck member, and an apertured guard disc positioned between said members and above said can, said disc having substantial area between said aperture and the periphery of the disc, the spacing of the bottom

of the guard disc from said line in said chuck member being equal to said given distance less a distance smaller than the thickness of a finger.

5. In a manually loaded can-closing machine the combination of a can-closing chuck member, a table member adapted to support the can to be closed, one of said members being mounted for movement from a first position toward the other of the members a given distance to bring a can placed on said table member into a sealing position in said chuck member with the top of the can at a given line in said chuck member, and a guard disc positioned between said members and above said can, said guard disc having a substantially central opening between the flat faces thereof, the size of said opening being greater than the cross-sectional dimensions of the can, said disc being substantially greater in external dimensions than the side of said opening to provide a wide face about at least the greater portion of said opening, the spacing of the bottom of the guard disc from said line in said chuck member being equal to said given distance less a distance smaller than the thickness of a finger.

6. The method of operating a manually loaded can-closing machine having a closing head, a vertically reciprocable can-supporting member, and an apertured plate therebetween positioned generally parallel to said member, said method comprising positioning said plate and said member, 25 in its lower position a sufficient distance apart to permit said can to be inserted therebetween only if the operator does not have a finger at the ends of the can adjacent said plate or member and thereafter raising said member to bring said can in contact with said head to close said can.

7. The method of operating a manually loaded can-closing machine having a closing head, a vertically reciprocable can-supporting member,

and an apertured plate therebetween and positioned generally parallel to said member, when said machine is used by an operator to close cans having a given height, said method comprising positioning said plate from said member in its lowest position a distance greater than the height of said can but less than the height of said can plus the thickness of the operator's fingers and thereafter raising said member to bring

10 said can in contact with said head to close said can.

8. A method of using a flat apertured plate with a vertically reciprocable can-closing machine having a closing head and a can supporting member and used for closing cans having a given height, said method including positioning said plate parallel to said member between said member and said head and spaced from said member a distance greater than said height, with said distance being insufficient to allow a can to be inserted therebetween if the finger of the operator is over either end of the can, and thereafter raising said member to bring said can in contact with said head to close said can.
